UNITED STATES PATENT OFFICE.

CHESTER H. BARNETT, OF LINCOLN, NEBRASKA.

MUSIC-LEAF TURNER.

1,033,656.

Specification of Letters Patent. Patented July 23, 1912.

Application filed March 8, 1911. Serial No. 612,986.

To all whom it may concern:

Be it known that I, CHESTER H. BARNETT, a citizen of the United States, and a resident of Lincoln, in the county of Lancaster, State of Nebraska, have invented a new and useful Improvement in Music-Leaf Turners, of which the following is a specification.

My invention relates to improvements in music leaf turners, and has for its object to provide a simple, cheap and efficient device adapted to be used in connection with pianos, organs, &c., for readily and quickly turning either forward or backward the leaves of sheet music or music books.

My invention consists in certain novel features of construction, arrangement and combination of parts as will be hereinafter fully described and pointed out in the claims, reference being had to the accompanying drawing, in which:

Figure 1 is a front elevation of the device; Fig. 2 is a central vertical section of same showing in section the upper and lower ends of the concentric operating shafts. Fig. 3 is a perspective view of the base portion with front removed and showing the operating mechanism; Fig. 4 is a fragmentary perspective view showing the music base support; Fig. 5 is a transverse section on line 5—5 of Fig. 4. Fig. 6 is a perspective view showing the clasp at the end of the arm for supporting outer upper corner of the sheets. Fig. 7 is a top plan view showing means for securing the leaf supporting arms to their respective operating shafts.

The base A of the device is a box-like structure and is divided into four sections by the partitions A'; in the lowest section and upon the floor of the same is slidably mounted the rack a which forms a push key. A pinion b is mounted on the lower end of shaft b', which shaft passes through the various sections and is journaled at its upper and lower ends; the rotation of pinion b and the shafts b' rotates pinion b² secured to shaft b' in the upper section of the base and said pinion b² meshes with the rack bar c which is wider at the central portion than at each end c', the central portion and each reduced end portion having a toothed edge; the wider central portion engages the pinion d mounted on the hol-

low shaft e mounted on another hollow shaft f which in turn is mounted on a solid center shaft g, all the shafts being suitably mounted in the base A. The hollow shaft e extends upwardly within the box-like standard H and carries at its upper end a sleeve e' secured thereto by a set-screw; the sleeve has an extension e² which is slotted to receive and hold an arm i which carries at its outer end the spring clasp r shown in Fig. 6. The arm i is pivotally secured at its inner end in the slotted sleeve extension e² by a bolt i² passing through the same, said bolt also securing one end of a spring i³ which carries a locking pin i⁴ which is forced through slotted extension e² and the inner end of arm i; by withdrawing the locking pin i⁴ the arm i may be swung upward on its pivot i². As stated, the shafts e and f are carried by a solid shaft g, that is, they are concentrically mounted; the solid shaft g is stepped at its lower end in the bottom wall of the base member and has mounted on it within the second section of the base the pinion g' which engages the rack g² (similar in construction to rack c); said rack g² being also engaged by the pinion g³ mounted on the shaft g⁴ in the second section, said shaft g⁴ carrying at its lower end the pinion g⁵ actuated by the rack key g⁶ mounted and operated in the same manner in guide g⁷ as the key a. As hereinbefore described, the shaft f which surrounds shaft g and is within shaft e has at its lower end the pinion f' which is within the third section or compartment of the base, said pinion being engaged by rack f² similar to rack c (previously described), which rack f² is engaged by pinion f³ mounted on shaft f⁴, carrying at its lower end the pinion f⁵ mounted and operating in the same manner by the rack key f⁶ as the key a hereinbefore described and guided by guide f⁷. By pushing in on key a the rack c rotates hollow shaft e and swings arm i to the left; pushing in on key f⁶ swings bar or arm j to the left and pushing in on key g⁶ swings arm h to the left; the right ends of the rack bars c, f² and g² are similarly reduced and provided with teeth which are engaged, respectively, by the pinions l, m and n mounted on shafts l', m', n', carrying at their lower ends pinions l², m², n², which are engaged by the

rack bars or keys l^3 , m^3 , n^3 held by the guides l^4 , m^4 , n^4 ; all these parts being similar to corresponding members on the left side of the device; by pushing in on the 5 keys l^3 , m^3 and n^3 the arms h , j and i are swung back to the left again. Of course, as many arms may be used as desired, and the necessary operating parts installed. On the ends of rack bars a , f^6 and g^6 and rack 10 bars l^3 , m^3 and n^3 are placed the heads or buttons A^2 , F and G and L , M and N .

The standard H , as before stated, is a box-like structure and may be open at the front side as shown or it may be closed. A shelf 15 H' having end extensions H^2 H^2 hinged thereto by hinges h^2 has a cut out portion fitting the standard H and the upwardly extending lugs or ears H^3 carrying inwardly projecting pins h^3 which rest on the 20 toothed rack h^4 mounted on each side of the standard H . The toothed rack h^4 is made integral with the plate h^5 which prevents the pins h^3 from being forced too far rearwardly; the teeth of the rack h^4 are made 25 flat on their upper surfaces on which the pins h^3 rest, but slant rearwardly on their vertical edges so that the pins h^3 may slide readily upward to the next tooth above. On the bottom of the base A a plate A^2 is secured, said plate having its front edge 30 curved downwardly, as at A^3 , to rest over the edge of the piano above the keyboard; the lower face of plate A^2 may have some soft substance, as fabric or rubber, to prevent 35 scratching of the wood-work of the piano or organ.

At the outer ends of the arms i , j and h are secured spring clasps r , s and t which are elongated and grasp the upper corners 40 of the sheet music; the arms i , j and h can be readily removed from their respective operating shafts, and the ends H^2 of the shelf folded on the section H' , whereupon the entire device can be packed in a small space; 45 indeed, the shelf H' may be entirely removed from the standard H and the entire device put in a receptacle large enough simply to receive the base A .

It will be seen that I provide a simple, 50 cheap and efficient music leaf turner free from springs or other delicate parts apt to break and get out of order.

I claim:

1. In a music leaf turner, the combination 55 with a base portion, a plurality of horizontal and longitudinally movable rack bars, a plurality of parallel vertical shafts mounted in said base, a plurality of pinions mounted on each shaft and adapted to engage the 60 aforesaid rack bars, a plurality of transversely movable rack bars adapted to engage pinions on the parallel vertical shafts, a standard extending upwardly from the base, a plurality of concentric shafts mounted 65 in said standard, pinions secured to the

lower ends of the concentric shafts adapted to be engaged by the longitudinally movable rack bars and leaf carrying arms extending horizontally from the upper ends of the concentric shafts.

2. In a music leaf turner, the combination 70 with a base, a plurality of horizontal and longitudinally movable bars arranged in tiers, each bar having a toothed central portion and end portions said end portions reduced in width and provided with teeth; a standard 75 extending upwardly from said base and carrying a plurality of concentric shafts therein, pinions mounted on the lower ends of the concentric shafts, leaf carrying arms extending 80 from the upper ends of the concentric shafts, a plurality of parallel vertical shafts mounted in the base, each shaft having a pinion at its lower end and another pinion, said last mentioned pinion engaging a reduced end of 85 one of the longitudinal bars, the central toothed portion of each bar engaging a pinion on the lower end of a concentric shaft, and transversely mounted toothed racks mounted to slidably engage the pinions on 90 the lower ends of the parallel shafts.

3. In a music leaf turner, the combination 95 with a base portion and vertical standard, of concentric shafts mounted in said standard, and leaf carrying means comprising a hub rigidly secured at the upper ends of the shafts, an arm pivotally secured to said hub and projecting therefrom, and a spring pin carried by the hub and adapted to engage the arm and lock it in a horizontal position, 100 and clasps at the outer ends of the arms.

4. In a music leaf turner, the combination 105 with a base portion and vertical standard, of concentric shafts mounted in said standard, and leaf carrying means comprising a hub rigidly secured at the upper end of each shaft, a bifurcated spoke extending horizontally from said hub, an arm pivotally held between the bifurcations, a spring pin mounted on the bifurcated spoke and 110 adapted to project through alined openings in the bifurcations and pivoted arm, and clasps at the outer end of the arm.

5. In a music leaf turner, the combination 115 with a base portion having compartments arranged in vertical tiers, a longitudinally movable bar mounted in each compartment, each bar having a central toothed portion and end portions, said end portions reduced in width and having teeth, a standard extending vertically from the base, a plurality 120 of concentric shafts mounted in said standard and base and carrying leaf supporting arms at their upper ends, pinions mounted on the lower ends of the concentric shafts, a plurality of parallel vertical shafts corresponding in number to the concentric shafts mounted in the base on each side of the standard, each vertical shaft carrying two pinions, one to engage a reduced end of a 125 130

longitudinal bar, said longitudinal bars engaging at their central toothed portion a pinion on the end of one of the concentric shafts, the other pinion on each of the parallel vertical shafts being secured to the lower end of said shafts and transversely slidabie rack bars mounted in the lower compartment of

the base on each side of the standard and engaging the pinions at the lower ends of the parallel vertical shafts.

CHESTER H. BARNETT.
